UNITED STATES PATENT OFFICE.

JAMES E. REID, OF MOORESTOWN, NEW JERSEY.

AIR COMPRESSOR FOR DENTAL AND OTHER PURPOSES.

Application filed November 11, 1926. Serial No. 147,702.

The principal objects of the present invention are, first, to provide a comparatively inexpensive, unitary or self-contained and silent running apparatus adapted to furnish an even or uniform supply of air under pressure and suitable for use by dentists and others; second, to obviate the use of separate air tanks and automatic stopping and starting mechanism; and third, to provide a simple and compact air compressor requiring for its operation comparatively little power.

Other objects of the invention will appear from the following description at the end of which the invention will be claimed and in the following description reference will be made to the embodiment of the invention selected for illustration in the accompanying drawings forming part hereof and in which

Figure 1 is an elevational view of an air compressor embodying features of the invention.

Figure 2 is a central sectional elevation of the right-hand end of the structure shown in Figure 1, and

Figure 3 is a sectional view taken on the line 3—3 of Figure 2.

In the drawings 1 is a generally cylindrical casing provided internally with a closed annular air chamber 2, Figure 2, dividing it into motor and pump chambers 3 and 4, and providing an opening 5 for the passage of the motor shaft 6. This casing is shown as mounted upon a stand 7 and a foot 8, and is provided with a handle 9 so that it is self-contained and portable as a unit. The diameter of the motor chamber is shown as larger than the diameter of the pump chamber and the difference in diameters is accommodated by the swell or bulge in the outside wall of the air chamber. There is an electric motor arranged in the motor chamber and with the exception of its shaft 6 and current connections 10 its parts are not shown because its construction is too well understood to require illustration or description. The motor shaft 6 extends through the opening 5 and projects into the pump chamber 4 which is shown as closed by a plate 11. There are a plurality of radially disposed pump cylinders 12 opening through the cylindrical wall 13 of the pump chamber, and the closed intake ends of these cylinders project beyond the wall 13 and are provided with check valves and air intake fittings 14. 15 are crosshead guides radiating from the opening 5 and arranged

in the pump chamber 4, and at the outside of one face of the air chamber 2. There is a crosshead guide for each pump cylinder. 16 generally is an eccentric mounted on the motor shaft 6, or more accurately on the end thereof, and it is located in the pump chamber and overlies the crosshead guides 15. This eccentric in the interest of silent running and small power consumption may well be made of a disc or roller 33 of hard fiber, bakelite or like material turnably mounted on a pin 32 eccentrically arranged on the end of the shaft 6. The pump plungers 17 are rigidly provided with rods 18 equipped with crossheads 19 working in the guides 15 and having flat faces 20 riding on the rim of the eccentric. 21 are springs pressing the rods into following relation with the eccentric and operating to retract the plungers after the eccentric has pushed them into their cylinders to compress air therein. In a sense the springs also operate to restore a part of the energy expended in compressing them. There are air connections 22 from the cylinders 12 to the air chamber 2, and there is an air offtake 23 from the air chamber 2 to the coupling 24 to which may be applied a hose for delivering the air wherever it may be required, for example, to a dentist's instrument. 80 Air is taken into the cylinders by openings at 25 having check valves 26, Figure 2, and is delivered under pressure from the cylinders past the check valves 27, Figure 2. 28 is an oil inlet, and 29 is an oil distributor attached to the end of the shaft 6, and taking oil from the reservoir 34.

The motor is directly connected without the intervention of gearing, and the pump pistons and piston rods are rigidly connected, 95 and the springs hold the flat faces 20 up to the disc 33 of bakelite or like material so that the machine runs silently. The supply of air is uniform because of the plurality of pumping cylinders. The device is compact 100 and small and portable, while efficient and simple and free from complications in both construction and operation. Moreover the casing may consist of a single casting in which case the core for the air chamber 2 may be removed through the plugged openings 30, and the other parts are simple and easily constructed and machined. The cap 31 serves to close the end of the motor chamber so that the casing is substantially closed.

It will be obvious to those skilled in the art that modifications may be made in details

of construction and arrangement and in matters of mere form without departing from the spirit of the invention which is not limited as to such matters or otherwise than as 5 the prior art and the appended claims may require.

I claim:

1. In an air compressor the combination of a generally cylindrical closed casing provided internally with a closed annular air chamber dividing it into motor and pump chambers and providing an opening for the passage of a motor shaft, a motor arranged in the motor chamber and having its shaft extending 10 through said opening and into the pump chamber, a plurality of radially disposed immovable pump cylinders opening through the cylindrical wall of the pump chamber, crosshead guides radiating from said opening and arranged in the pump chamber and at the outside of one face of the air chamber, a crank pin, on the motor shaft and in the pump chamber, a disk on the crank pin, pump plungers having rigidly connected 15 rods provided with crossheads working in said guides and riding on the disk, springs pressing the rods into following relation with the eccentric, valved pipe connections from the cylinders to the air chamber, and 20 an air offtake pipe from the air chamber.
2. In an air compressor the combination of a cylindrical casing, a closed annular air chamber dividing the casing into motor and pump chambers and providing an opening between them, a motor shaft projecting from the motor chamber through said opening into the pump chamber, radially disposed fixed pump cylinders opening through the cylindrical wall of the pump chamber and having 25 their closed ends projecting beyond the same, pump plungers provided with rigidly connected rods, a crank pin, on the motor shaft, 30

a disk on the crank pin, for operating said rods in one direction, springs for operating the rods in the other direction, crossheads 45 and crosshead guides for the rods, and air connections arranged outside of the casing, substantially as described.

3. In an air compressor the combination of a generally cylindrical closed casing provided internally with a closed annular air chamber dividing it into motor and pump chambers and providing an opening for the passage of a motor shaft, a motor arranged in the motor chamber and having its shaft 50 extending through said opening and into the pump chamber, a plurality of radially disposed fixed pump cylinders opening through the cylindrical wall of the pump chamber, crosshead guides radiating from said opening and arranged in the pump chamber and at the outside of one face of the air chamber, an eccentric pin on the end of the motor shaft and in the pump chamber, a disc revolvably mounted on said pin, pump plungers having 55 rigidly connected rods provided with crossheads working in said guides and with flat faces riding on the disc, springs pressing the flat faces into following relation with the disc, valved pipe connections from the cylinders to the air chamber, and an air offtake pipe from the air chamber.

4. In an air compressor the combination of a driving shaft, a series of open ended fixed cylinders radially disposed in respect to the shaft with their open ends confronting the shaft, a pin eccentrically mounted on the end of the driving shaft, a disc turnably mounted on the pin, plungers provided with rigidly connected spring pressed rods having flat 60 faces riding on the rim of the disc, and crossheads and crosshead guides arranged in proximity with said flat faces.

JAMES E. REID.
